UNITED STATES PATENT OFFICE.

FRANK A. FEIEREISEL, OF CHICAGO, ILLINOIS, ASSIGNEE TO SHORTWRITER COMPANY,
OF WILMINGTON, DELAWARE, A CORPORATION OF DELAWARE.

WRITING-MACHINE.

1,242,167.

Specification of Letters Patent.

Patented Oct. 9, 1917.

Application filed January 8, 1916. Serial No. 70,929.

To all whom it may concern:

Be it known that I, FRANK A. FEIEREISEL, a citizen of the United States, residing at Chicago, in the county of Cook and State of Illinois, have invented certain new and useful Improvements in Writing-Machines, of which the following is a specification.

This invention relates to writing machines and more particularly to improvements in striking mechanism therefor.

It is an object of my invention to provide, in a writing machine, means whereby the key and type bars are rigidly maintained in proper alinement so that lateral movement, which might result in slurring the letters printed is effectively prevented.

A further object of my invention is the provision of a simple and effective operating connection between the key and type bars, whereby the type may be caused to exert the desirable pressure during the printing operation with a minimum application of force at the keys.

A still further object of my invention is the provision of a striking mechanism for writing machines involving a minimum number of parts, whereby the manufacture of the machine is simplified and the weight thereof is materially reduced.

Further objects and advantages of my invention will be apparent as it is better understood by reference to the following specification when read in connection with the accompanying drawing, illustrating a preferred embodiment thereof, in which—

Figure 1 is a plan view of the frame of the machine with the coöperating key and type bars and the means for maintaining the bars in proper alinement;

Fig. 2 is a vertical section on the line 2—2 of Fig. 1;

Fig. 3 is a horizontal section on the line 3—3 of Fig. 2;

Fig. 4 is a vertical section on the line 4—4 of Fig. 1;

Fig. 5 is a detail in perspective of an integral member to engage the contiguous extremities of the key and type bars, and

Fig. 6 is a detail in perspective of the means on the key bars providing an operating connection between the key and type bars.

Referring to the drawing, 1 indicates a suitable frame for supporting the various parts presently to be described. A shaft 2

is secured to the frame 1 adjacent the forward extremity thereof and pivotally supports a plurality of key bars 3, each provided with a key 4 at its outer end. The inner ends of the key bars 3 are provided with upwardly extending arms 5 having slots 6 therein.

Pivotedly mounted on a shaft 7 rearwardly of the shaft 2 are a plurality of bell-crank levers 8, each having type characters 9 near the extremities of one of the arms thereof and a curved extension 10 at the extremities of the other arms thereof, the extensions 10 being adapted to engage the slots 6 in the arms 5 of the key bars 3. Springs 11, secured to the key bars 3 and to a base plate 12 of the frame 1 serve to maintain the key and type bars in their normal position.

From the foregoing it will be apparent that when one or more of the keys 4 are depressed the corresponding key bars 3 and bell crank levers 8 will be rotated on their respective shafts 2 and 7 to move the type characters 9 into engagement with the ribbon 13, impression-receiving material 14 and platen 15, the latter elements being illustrated in dotted lines in the drawing. During this operation the curved extensions 10 of the bell-crank levers 8 slide in the slots 6. By the use of this form of connection between the key and type bars it is not only possible to materially reduce the length of the key bars, which in ordinary machines of this type are pivoted at the rearward extremity of the machine, but, as will be readily understood, sufficient leverage is provided to cause the type characters 9 to exert sufficient pressure at the printing point with a minimum application of force to the keys, and a rigid connection between the key and type bars is assured.

To maintain the key and type bars in proper alinement a spacing washer 16 is mounted on the shaft 2 between each of the key bars 3. A plate 17 is secured to the frame 1 at 18 and is provided with a plurality of slots 19 in which the extremities of the bell-crank levers 8 are disposed. The plate 17 is provided with a plurality of integral down-turned spaced arms 20 between which the contiguous extremities of the key bars 3 are disposed. A plate 21 is secured to the frame at 22 adjacent the printing point and is provided with a plurality of spaced arms 23, providing slots in each of

which the upper end of one of the arms of the bell-crank levers 8 is disposed. It will be understood from the foregoing that the key bars and the bell-crank levers 8, forming the type bars, are each guided at two separated points and that lateral movement thereof is therefore effectually prevented. The integral plate 17, having guiding means for the contiguous ends of the key and type bars, provides a simple and compact means for accomplishing the desired result.

It will be apparent that I have perfected an extremely simple and effective striking mechanism for writing machines, whereby numerous desirable results are obtained.

It will be further apparent that various changes may be made in the form, construction and arrangement of the parts without departing from the spirit and scope of the invention or sacrificing any of its material advantages, the form hereinbefore described being merely a preferred embodiment thereof.

I claim:

25 1. In a writing machine, the combination of a frame, a shaft adjacent the forward extremity of said frame, a plurality of key bars pivotally mounted on said shaft, separating means on said shaft between said key bars, a plurality of type bars pivotally mounted rearwardly of said shaft, interengaging means on said key and type bars, whereby the latter are actuated, an integral member having means thereon to engage said key and type bars to maintain them in proper alinement, and separate means engaging said type bars above said member to prevent lateral movement thereof.

2. In a writing machine, the combination of a plurality of pivoted type bars, a plurality of pivoted key bars, slidably interengaging means on said key and type bars, whereby the latter are actuated by the for-

mer, separating means between said key bars at their pivotal points, means for engaging said key and type bars at their contiguous extremities to maintain them in proper alinement, and means to engage the opposite extremities of said type bars to prevent lateral movement thereof.

3. In a writing machine, the combination of a plurality of pivoted bell-crank levers, each provided with type characters adjacent the extremity of one arm thereof, a plurality of pivoted key bars having means thereon to embrace the extremities of the other arms of said bell-crank levers, separating means between said key bars at their pivotal points, means for engaging the extremities of said key bars and the pivotal portions of said bell-crank levers to maintain the latter in proper alinement with said key bars, and means engaging the type character-bearing arms of said bell-crank levers to prevent lateral movement thereof.

4. In a writing machine, the combination of a frame, a shaft adjacent the forward extremity of the frame, a plurality of key bars pivotally mounted on said shaft, a shaft supported in said frame medially thereof, a plurality of type bars pivotally mounted on said second-mentioned shaft, interengaging means on said key and type bars whereby the latter are actuated by the former, an angular plate having slots to receive the pivotally mounted ends of said type bars and a downwardly turned portion having alined slots to receive extensions of said key bars, a platen with which said type bars coöperate, and a slotted plate adjacent said platen to prevent lateral movement of the free ends of said type bars.
